UNITED STATES PATENT OFFICE.

HORACE LEHR, OF EASTON, PENNSYLVANIA.

DESIGN FOR A PIANO.

Application filed March 15, 1923. Serial No. 5,478. Term of patent 3½ years.

To all whom it may concern:

Be it known that I, HORACE LEHR, a citizen of the United States, residing at Easton, in the county of Northampton and State of Pennsylvania, have invented a new, original, and ornamental Design for Piano, as shown in the accompanying drawing and described in the following specification.

The figure represents a perspective view of my new design of piano.

I claim:

The ornamental design for a piano as shown and described.

HORACE LEHR.

Witnesses:

HORACE A. LEHR,
ETHEL C. LILLY.
